United States Patent Office

Des. 232,210

Patented July 30, 1974

232,210

TOASTER

Harry Hentschel, Munich, Germany, assignor to Siemens-Electrogerate GmbH, Berlin and Munich, Germany

Filed Apr. 28, 1972, Ser. No. 248,786

Claims priority, application Germany Oct. 29, 1971

Term of patent 14 years

Int. Cl. D7—02

U.S. Cl. D7—93

FIG. 1 is a top front perspective view of a toaster showing my new design;

FIG. 2 is a side elevational view thereof; and

FIG. 3 is a top plan view thereof.

The rear and end views opposite those shown in FIGS. 1 and 2 are identical thereto.

I claim:

The ornamental design for a toaster, substantially as shown and described.
